UNITED STATES PATENT OFFICE.

WLADYSLAW SLAWSKI, OF GLASSBORO, NEW JERSEY.

WRECK-INDICATING BUOY.

1,294,549.

Specification of Letters Patent.

Patented Feb. 18, 1919.

Application filed October 9, 1918. Serial No. 257,477.

To all whom it may concern:

Be it known that I, WLADYSLAW SLAWSKI, a citizen of Russia, residing at Glassboro, in the county of Gloucester and State of 5 New Jersey, have invented certain new and useful Improvements in Wreck-Indicating Buoys, of which the following is a specification.

This invention relates to certain new and 10 useful improvements in wreck indicating buoys and has among its objects the provision of such type of device which is extremely durable in construction and efficient in operation.

15 The primary object of the present invention is to provide the float member of a wreck indicating buoy with an electrical illuminating means whereby the float may be visible at night, novel means being provided to close the circuit of the electrical illuminating means as well as to hold the circuit open when the buoy is operatively positioned upon the deck of a ship.

20 With the above general objects in view and others that will become apparent as the nature of the invention is better understood, the same consists in the novel construction, form and arrangement of parts hereinafter more fully described, shown in the accompanying drawings and claimed.

25 In the accompanying drawings, in which like characters of reference indicate corresponding parts throughout the several views,

30 Figure 1 is a side elevational view of a ship floating upon the water and having the present invention associated therewith;

35 Fig. 2 is a view of the ship when sunk with the indicating buoy of the present invention floating upon the surface of the water;

40 Fig. 3 is an enlarged detail view of the present invention in side elevation and attached to the fragment of the deck of a ship which is shown in vertical section;

45 Fig. 4 is a vertical sectional view taken through a fragment of a tube carried by the float and showing the illuminating means;

50 Fig. 5 is a horizontal sectional view of the device shown in Fig. 4 taken substantially upon line 5—5 of Fig. 4;

55 Fig. 6 is a detail view in central transverse section of the movable circuit closing member; and

Fig. 7 is a diagrammatic view of the circuit closing means, the electric lamp and the

battery, and showing the circuit between the same.

Referring more in detail to the several views, the present invention is shown applied to a ship 5 and is arranged at any desirable point upon the deck 6 thereof. A suitable depending frame 7 is secured against the under face of the deck 6 as at 8, and has a transverse base member 9 in which the axle 10 of a vertical reel 11 is journaled, 60 said reel being provided with a pulley 12 at the lower end thereof by means of which the same may be rotated, either by hand, or by belt gearing to any suitable motor, not shown. 70

A tube 13 has its upper end in registry with an opening 14 provided through the deck 6 and has its lower end rigidly connected to a flared guide 15 from the base of which are extended curved supporting legs 75 16 whose flanged lower ends 17 are secured as at 18, to the base member 9 of the frame 7.

A flared band 19 is rigidly supported horizontally a suitable distance above the 80 deck 6 concentric with the aperture 14 by means of legs 20 whose lower flanged ends are secured as at 21 to the deck 6 and whose upper ends are rigidly fastened as by means of rivets 22 to said band 19. 85

A float member 23 is adapted to be supported by the band 19 as shown in Fig. 3 with the lower frusto-conical portion of said float fitting snugly in the band 19 as illustrated, said float having a tube 24 extending axially therethrough from its lower end to a point some distance beyond the upper end thereof. 90

A suitable flag or other signal 25 may be attached to the upper end of the tube 24, 95 and at a point slightly below the flag 25, the tube 24 is provided with a plurality of openings 26 which are effectively closed against the entrance of water by means of glass lenses 27. A transverse partition 28 is rigidly fastened within the tube 24 at a point slightly below the openings 26 and supports an electric lamp 29 whose base 30 rests thereon as clearly shown in Fig. 4. 100

A second horizontal partition 31 is disposed within the tube 24 at a point below the partition 28 and supports a suitable electric battery 32. At a point below the partition 31, an insulator block 33 is secured within the tube 24 by means of screws 34 or 105 110

the like, and said block 33 has a contact plate 35 secured to the upper face thereof which is electrically connected by means of a wire 36 to one terminal 37 of the battery 32. 5 A second insulator block 38, similar to the block 33 is secured within the tube 24 preferably at a point directly opposite to the block 33. Block 38 has a contact plate 39 secured to the upper face thereof which is 10 electrically connected to one terminal 40 of a filament 41 of the lamp 29 by means of a wire 42 (see Figs. 4 and 7). The other terminal 43 of the filament 41 is connected electrically by means of a wire 44 to the 15 other terminal 45 of battery 32. It will now be obvious that when electrical connection is established between plates 35 and 39, the filament 41 of lamp 29 will become incandescent, and in order to make this connection between plates 35 and 39, a means herein-after described is provided.

In practice, a suitable cable 46 is helically wound upon the reel 11, one end of said cable being attached to said reel and 25 the other end thereof being attached, as at 47, to the lower end of a vertical rod 48 which extends from a point slightly below the lower end of float 23 to a point within the tube 24 above the blocks 33 and 38 and 30 below the partition 31. It is noted that the cable is extended from the reel 11 through the guide 15 and tube 13 and then attached to the rod 48.

A horizontal pulley-like plate 49 of insulating material is rigidly secured upon the 35 upper end of rod 48 as clearly shown in Figs. 4, 5 and 6 and said disk 49 has a suitable metallic band 50 embedded therein concentric with the rod 48, said band 50 being 40 arranged to project a suitable distance below the disk 49 as shown more clearly in Fig. 6.

A suitable guide 51 is rigidly fastened to extend transversely within the tube 24 and 45 has the rod 48 extended therethrough so as to guide said rod in its longitudinal movements axially of the tube 24. When the float is positioned upon the deck of a ship, as illustrated in Fig. 3, disk 49 is maintained in its upper position by means of a 50 spring-pressed latch 52 which is carried by the tube 24 and is arranged so that its inner end engages in the groove 53 of the disk 49. It will be seen that when the disk is maintained in this position, the band 50 does not contact the plates 35 and 39 and therefore the lamp 29 is not lighted. It is also noted that the spring 54 is only slightly tensioned to inwardly move the latch 52 so 55 that only a slight pull is necessary to release the disk 49 from said latch.

In operation, the float 23 is disposed as shown in Figs. 1 and 3 and, should the ship 5 sink to the position shown in Fig. 2, the 60 float 23 will be allowed to float upon the

surface of the water by the unwinding of cable 46 from the drum 11 although said buoy 23 will at all times remain connected to the ship 5. As the cable 46 is connected to rod 48, any pull upon said cable, such as 70 caused by sudden sinking of the ship 5 or movement of the buoy 23 from the action of the waves, disk 49 will be pulled out of engagement with latch 52 through the agency of rod 48 and will by its own weight 75 lower so that band 50 bridges plates 35 and 39 at which time the lamp 29 is lighted so that the float may be readily discerned at night time.

From the foregoing description, it will 80 be seen that a serviceable wreck indicating buoy has been provided which possesses great utility and which is effective in operation for the intended purposes, it being noted that the signal or flag 25 will be of 85 value in case the sinking of the ship 5 occurs in day time or in case the battery 32 becomes worn out before the buoy is discovered.

It is believed that the construction and 90 operation as well as the advantages and utility of the present invention will be readily understood from the foregoing description by those skilled in the art, and while the form of the invention herein shown and described is what is believed to 95 be the preferred embodiment thereof, it is nevertheless to be understood that minor changes may be made in the detail construction, form and arrangement of parts without departing from the spirit and scope of 100 the invention as claimed.

What is claimed is:

1. A wreck indicating buoy including a float having a tube extended therethrough from the lower end thereof to a point beyond the upper end thereof, lens covered openings in said tube above said float, an electric lamp within said tube opposite said lenses, an electrical circuit including a battery connected to said lamp and arranged 105 below the latter in said tube, said circuit including a pair of contacts arranged within said tube below said lamp, a reciprocable circuit closer arranged within said tube above said contacts, a spring pressed latch carried by said tube arranged to engage said circuit closer to releasably maintain the same in raised open position, a rod slidably arranged within said tube and float and having said circuit closer mounted upon the 110 upper end thereof, and a flexible cable having one end attached to the lower end of said rod and adapted to have its other end connected to a ship, substantially as and for the purposes described. 115

2. A wreck indicating buoy comprising in combination with the deck of a ship having an aperture therethrough, a float, means upon the deck of said ship to support said float above said aperture, a frame suspended 120

from said deck having a base member arranged below said aperture, a vertical reel rotatably supported upon said base member, a tube below said deck having its upper end in registry with said aperture and provided with a flared cable guide at the lower end thereof positioned above said reel, means connected to the bottom of said flared cable guide and to said base member of said

frame to support said tube and cable guide 10 above said reel, a cable normally wound upon said reel extended through said guide, tube, and deck aperture and connected to said float, and means upon the lower end of said reel to rotate the latter to wind said 15 cable thereon.

In testimony whereof I affix my signature.
WLADYSLAW SLAWSKI.
